(57) **CLAIM**

The ornamental design for a charger for electric vehicles, as shown and described.

DESCRIPTION

FIG. 1 is a perspective view of a charger for electric vehicles showing the new design;

FIG. 2 is a front elevation view thereof;

FIG. 3 is a back elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a second perspective view thereof.

The broken lines shown in FIG. 4 are for the purpose of illustrating portions of the charger for electric vehicles that form no part of the claimed design.
